US00D612855S

(12) **United States Design Patent**
Waterman

(10) **Patent No.:** **US D612,855 S**
(45) **Date of Patent:** **** Mar. 30, 2010**

(54) **HAND HELD OPTICAL IMAGER HAVING SIDE TRIGGERS**

(75) Inventor: **Mark D. Waterman**, North Syracuse, NY (US)

(73) Assignee: **Jadak, LLC**, North Syracuse, NY (US)

(**) Term: **14 Years**

(21) Appl. No.: **29/337,719**

(22) Filed: **May 28, 2009**

(51) **LOC (9) Cl.** **14-02**

(52) **U.S. Cl.** **D14/429**

(58) **Field of Classification Search** **D14/420, D14/426-430, 453, 346, 341, 347, 412, 138, D13/107, 184; 358/473; 235/462.43, 462.45, 235/462.47, 462.48, 462.44, 462.46, 487, 235/472.01, 472.02, 145 A, 145 R; 16/110.1, 16/430, 431; 439/133, 135; 709/219, 201; 710/73; 320/114, 115, 123; 361/679; 382/313, 382/321; 455/575.1, 561, 572; D10/78; 324/426; D3/273; D18/7; 345/156, 168, 345/169, 172, 173, 87**

(57) **CLAIM**

The ornamental design for a hand held optical imager having side triggers, as shown and described.

DESCRIPTION

FIG. 1 is a perspective view of a new and ornamental design for a hand held optical imager having side triggers in which portions shown in broken line are for illustrating environment only and are not claimed;

FIG. 2 is a second perspective view thereof;

FIG. 3 is a bottom plan view thereof;

FIG. 4 is a side elevation thereof;

FIG. 5 is a top plan view thereof;

FIG. 6 is a rear elevation thereof; and,

FIG. 7 is a front elevation thereof.

The broken line elements in the drawings are not claimed.
